HANDLE FOR AUTOGRAPHIC REGISTER

Dana W. Mox, Glenview, Ill., assignor to Uarco Incorporated, Chicago, Ill., a corporation of Illinois

Filed Sept. 20, 1960, Ser. No. 62,213

Term of patent 14 years

(Cl. D64—11)

FIG. 1

FIG. 2

FIG. 4

Fig. 1 is a side elevational view of a handle for an autographic register showing my new design;

Fig. 2 is a top plan view thereof;

Fig. 3 is a front elevational view; and

Fig. 4 is a rear elevational view thereof.

I claim:

The ornamental design for a handle for an autographic register, as shown.
